(57) **CLAIM**

The ornamental design for a number plate, as shown and described.

DESCRIPTION

FIG. 1 is a perspective view of a number plate showing my new design.

FIG. 2 is a front view of the number plate.

FIG. 3 is a top view of the number plate.

FIG. 4 is a bottom view of the number plate.

FIG. 5 is a rear view of the number plate; and,

FIG. 6 is side view of the number plate, the opposite side being a mirror image thereof.

The particular features of the claimed design reside in the shape and configuration of the number plate. The broken line showing of numbers and letters is included for the purpose of illustrating environmental subject matter and forms no part of the claimed design.
